PIPE

Fulvio De Fazi, New York, N. Y., assignor of one-third to Alfonse Viviani and one-third to Hugo Melaragno, both of New York, N. Y.

Application June 26, 1939, Serial No. 281,098

10 Claims. (Cl. 131—215)

The present invention pertains to tobacco smoking implements and is particularly concerned with underslung pipes of the type having its smoke conducting mouth piece portion removably but frictionally associated with a laterally extending nipple disposed at the upper part of the bowl and communicating with the interior of the latter and with the mouth piece portion. One aspect of the invention deals with a pipe of the character referred to wherein the bowl thereof is provided with means whereby it may be conveniently located on a supporting surface without causing involuntary tilting of the pipe both longitudinally and transversely thereof and during such relation the mouth piece portion or bit is disposed substantially parallel to the supporting surface and appreciably spaced therefrom. In another aspect of the invention, the bowl is provided with a separate receptacle which communicates with the tobacco receiving concavity of the bowl and serves as means for collecting products of condensation or saliva separated from the smoke fumes, thus insuring a relatively dry smoke to the user. In another aspect of the invention, serviceable and cooperative means for appropriately closing the saliva collecting receptacle or casing has been provided and such cooperative closure means is suitably disconnectably interlocked with the upper part of the bowl and transversely thereof and constitutes means for frictionally but removably sustaining a reduced inner part of the mouth piece portion of the pipe. Other aspects, objects, advantages, and structural and functional features of the invention will be apparent from the teachings of the following detailed description considered in the light of the accompanying drawing which illustrates a preferred embodiment of the invention and wherein:

Fig. 1 is a perspective view of the underslung pipe according to my invention.

Fig. 2 is a plan view of Fig. 1.

Fig. 3 is a longitudinal sectional view on the line 3—3 of Fig. 2.

Fig. 4 is a sectional view on the line 4—4 of Fig. 3.

Fig. 5 is a sectional view on the line 5—5 of Fig. 3.

Fig. 6 is a perspective view of the so-called butterfly closure for the saliva collecting receptacle of the bowl.

Fig. 7 is an elevational view of the receptacle saliva collecting well or chamber.

Fig. 8 is a plan view of Fig. 7, and

Fig. 9 is a sectional view of Fig. 7.

Illustrative of the embodiment disclosed, the pipe generally denoted P comprises a bowl B, and a mouth piece portion M. Specifically however the bowl includes a body having the expanded substantially cylindrically shaped part 5 10 integral with base 11 including a lower rectilinear face 12 and an interior tobacco receiving concavity 13.

Integral with the body of the bowl which may be of a suitable wood or of any appropriate material is the contracted portion 14 which includes a vertically arranged bore or well 15 the walls of which frictionally hold and secure the cylindrical and hollow container or receptacle 16 having an uninterrupted bottom wall 17. Container 16 constitutes means for receiving the products of concentration separated from the smoke fumes after the latter have entered the orifice 18 at the upper end of the saliva collecting receptacle.

The smoke fumes of course originate in the concavity 13 and are drawn through the inclined or biased channel 19 into orifice 18 and according to the invention these fumes as they flow into orifice 18 impinge the rectilinear face 19 of the closure locking member generally designated L which embodies a head or key 20 having a central expanded part 21 provided with curved sides 22 merging with rectilinear sides 23 of the laterally extending lugs 24 integral with the expanded and curved part 21 from which the partly curved shank 25 depends and it is this shank which embodies a smoke fume impinging rectilinear vertical face 19 which is provided with an opening 26 in alignment with opening 27 of the saliva collecting receptacle or chamber 16 and in alignment with bore 28 of the hollow nipple 29 integral with and extending laterally of the upper part of the bowl.

The mouth piece portion or bit M embodies the usual stem 30 provided with the elongated bore 31 which communicates with the bore of the fixed tube 32 carried by the stem. This tube projects beyond the annular reduced portion 33 of the stem which comprises a vertical annular shoulder 34 cooperating with the annular end face 35 of the nipple to limit the insertion of the reduced portion 33 into bore 36 of the nipple 29 and to limit the insertion of the inner end of the fixed tube 32 into the receptacle 16 through the expanded bore 36 of the nipple, opening 27 of the receptacle 16, and opening 26 of the depending shank 25 of the so-called "butterfly" closure lock L which has a central expanded part removably fitting into the upper end of the bore 15 and its laterally extending lugs 24 re-

movably fit in the diametrically disposed notches 37 of the reduced portion 14 of the bowl.

In the assembled relation of the several parts of the pipe, the marginal portion 40 of the lower 5 face of the expanded portion 21 of the locking closure L is seated on the upper part or rim of the receptacle 16. In such relation the upper surface of the lock is substantially flush with the upper surface of the bowl. Also the rectilinear 10 face 19 of the depending shank 25 is spaced from an adjacent part of the bore of receptacle or well 16 to define a smoke conducting path. Moreover with the closure lock positioned as just described, the opening 26 in the depending shank 25 is in 15 alinement with the opening 27 of the receptacle 16 and with bore 28 of the nipple 29. If therefore tube 32 be inserted into the nipple, the inner end of this tube will be tightly but removably projected into the opening 26 of the depending 20 shank 25 until flange or shoulder 34 abuts end face 35 of nipple 19. It follows that in the assembled relation of the locking closure and the bowl, the tube 32 of the mouth piece portion cooperates with the closure lock to hold the latter 25 against its seat, to wit, against the upper rim of receptacle 16.

In operation, smoke fumes drawn through the bore 19' pass into orifice 18 and strike the rectilinear wall 19 which permit the products of condensation to collect and drip downwardly into the bottom of the receptacle. However the fumes now appreciably drier are drawn into tube 32 and to the communicating bore 30 to reach the mouth of the smoker.

35 Where it is desired to cleanse the parts of the pipe, the stem 30 may be readily disconnected from the nipple by merely slidably withdrawing the reduced portion 33 of the stem out of the bore 36 of nipple 19. This action removes or unlocks 40 the inner end of tube 32 from the closure key L. Consequently the latter may be conveniently detached from the upper part of the bowl and this is readily accomplished by grasping end faces 41 of lugs 24 and lifting upwardly relative to the 45 bowl. Thus access may be had to the saliva receptacle to clean the latter.

As many changes could be made in the above described construction and many widely different species or structural embodiments could be devised without departing from the scope thereof, it 50 is intended that all matter hereinbefore described in the specification and illustrated in the accompanying drawing shall be interpreted as illustrative and not in a limiting sense.

55 I claim:

1. In a pipe, a bowl comprising an expanded part having a tobacco receiving concavity and a reduced part comprising a receptacle in communication with said concavity and including spaced 60 notches; said receptacle having an aperture, a key having an expanded centrally arranged portion seated on the upper part of said receptacle and including laterally extending means removably received by said notches and including a 65 shank removably projectable into said receptacle and including a bore, said receptacle having means cooperating with said key to locate said bore in alinement with said aperture, a nipple extending laterally of said reduced part of said bowl 70 and in communication with said concavity, and a smoke conducting stem removably carried by said nipple and having means for detachably interlocking with the wall of said bore to prevent removal of said shank from said receptacle and 75 said laterally extending means from said notches.

2. A pipe bowl and mouth piece assembly wherein in the connection between the mouth piece and the pipe bowl comprises a transverse slot across the top part of said bowl and a chamber below said slot, the transverse slot comprising a central 5 enlarged opening above said chamber and spaced notches in said bowl, a key fitting in said chamber and having a central enlarged part fitting within said enlarged opening and having wings extending laterally beyond the exterior wall surface of 10 said bowl and fitting into said notches and having their upper surfaces substantially flush with the top surface of said bowl, the key having a bore, a tube extending from said mouth piece and projecting within said bore, the walls of said slot characterizing means whereby when the key is inserted therein said bore will be in direct alinement with the path of movement of said mouth piece when assembling the latter with said bowl. 15

3. A pipe bowl and mouth piece assembly wherein in the connection between the mouth piece and the pipe bowl comprises a transverse slot across the top part of said bowl and a chamber below said slot, the transverse slot comprising a central 20 enlarged opening above said chamber and spaced notches in said bowl, a key having a central enlarged part fitting within said enlarged opening and having wings extending laterally beyond the exterior wall surface of said bowl and fitting into 25 said notches and having their upper surfaces substantially flush with the top surface of said bowl, the key having a depending stem fitting into said chamber and having a bore, a tube extending from said mouth piece and projecting within said bore, the walls of said slot characterizing means whereby when the key is inserted therein said bore will be in direct alinement with the path of movement of said mouth piece when assembling the latter with said bowl. 30

4. A pipe bowl and mouth piece assembly wherein in the connection between the mouth piece and the pipe bowl comprises a transverse slot across the top part of said bowl and a chamber below

40 said slot, the transverse slot comprising a central enlarged opening above said chamber and spaced notches in said bowl, a key having a central enlarged part fitting within said enlarged opening and having wings extending laterally beyond the exterior wall surface of said bowl and fitting into 45 said notches and having their upper surfaces substantially flush with the top surface of said bowl, the key having a depending stem arranged within said chamber and including a bore and having a wall spaced from an adjacent wall of said chamber to define a passageway, a tube extending from said mouth piece and projecting within said bore, the walls of said slot characterizing means whereby when the key is inserted therein said bore will be in direct alinement with the path of movement of said mouth piece when assembling the latter with said bowl. 50

5. A pipe bowl and mouth piece assembly wherein in the connection between the mouth piece and the pipe bowl comprises a transverse slot across the top part of said bowl and a chamber below said slot, the transverse slot comprising a central 55 enlarged opening above said chamber and spaced notches in said bowl, a key having a central expanded part fitting within said enlarged opening and having wings extending laterally beyond the exterior wall surface of said bowl and fitting into 60 said notches and having their upper surfaces substantially flush with the top surface of said bowl, the key having a bore, a tube extending from said mouth piece and projecting within said bore, the walls of said slot characterizing means whereby when the key is inserted therein said bore will be in direct alinement with the path of movement of said mouth piece when assembling the latter with said bowl. 65

70

75

walls of said slot characterizing means whereby when the key is inserted within said slot said bore will be in direct alinement with the path of movement of said mouth piece when assembling the latter with said bowl, said key characterizing a closure for said slot and said wings projecting slightly beyond the sides of said bowl to facilitate removal of said key from said bowl subsequent to the removal of said stem from said bowl.

16 6. A combined moisture collector and tobacco holding bowl and mouth piece comprising a receptacle having a gap in communication with a smoke conducting opening of said bowl and including an oppositely arranged aperture adapted 15 to receive said mouth piece, a closure for said receptacle and fitting in said bowl, said closure having a recess forming with said receptacle a smoke conducting passageway, said receptacle having positioning means, said closure having a bore, said 20 closure having means cooperating with said positioning means to locate said bore in alignment with said aperture and having a formation whereby in one position thereof within said receptacle said mouth piece is adapted to be received within 25 said aperture and bore, the walls of said passageway constituting condensate receiving surfaces whereby one surface of said passageway deflects smoke to the opposing surface of said receptacle whereby said smoke contacts said surfaces prior 30 to movement thereof into said mouth piece.

7. A combined moisture collector and tobacco holding bowl and mouth piece comprising a receptacle having a gap in communication with a smoke conducting opening of said bowl and including an oppositely arranged aperture adapted 35 to receive said mouth piece, a closure for said receptacle and comprising a head having a central expanded part and reduced wings extending laterally beyond the exterior wall surface of said 40 bowl and fitting in correspondingly shaped transversely arranged slots in said bowl and having their upper surfaces substantially flush with the top surface of said bowl, said closure having a shank including a rectilinear wall spaced from 45 an opposing wall of said receptacle to define a smoke conducting passageway, said shank having a bore, said receptacle having positioning means cooperating with said closure to locate said bore in alinement with said aperture and 50 having a formation whereby in one position thereof within said receptacle said mouth piece is adapted to be received within said aperture and bore, the walls of said passageway constituting condensate receiving surfaces whereby one 55 surface of said passageway deflects smoke to the opposing surface of said receptacle whereby said smoke contacts said surfaces prior to movement thereof into said mouth piece.

8. A combined moisture collector and tobacco 60 holding bowl and mouth piece comprising a receptacle having a gap in communication with a smoke conducting opening of said bowl and including an oppositely arranged aperture adapted 65 to receive said mouth piece, a closure for said receptacle and comprising a head having a central expanded part and having laterally extending reduced wings fitting in correspondingly shaped transversely arranged aligned slots in said bowl, said closure having a depending shank 70 including a rectilinear wall spaced from an op-

posing wall of said receptacle to define a smoke conducting passageway, said shank having a bore, said receptacle having positioning means cooperating with said closure to locate said bore in alinement with said aperture and having a formation whereby in one position thereof within said receptacle said mouth piece is adapted to be received within said aperture and bore, the walls of said passageway constituting condensate receiving surfaces whereby one surface of said 10 passageway deflects smoke to the opposing surface of said receptacle whereby said smoke contacts said surfaces prior to movement thereof into said mouth piece, said wings projecting slightly beyond the sides of said bowl to facilitate removal of said closure from said bowl pursuant to the removal of said mouth piece from said bowl.

9. In a pipe, a bowl comprising an expanded part having a tobacco receiving concavity and a reduced part comprising a receptacle in communication with said concavity and including spaced notches; a key having an expanded centrally arranged portion removably seated on the upper part of said receptacle and including laterally extending means removably received by said notches and including a shank removably projectable into said receptacle and depending from said centrally arranged portion and having a smoke impinging substantially flat face spaced from a portion of an inner wall of said receptacle, said shank having a bore, said receptacle having an opening, said laterally extending means cooperating with the walls of said notches for positioning the wall of said bore in alinement with said opening, a nipple extending laterally of said reduced part of said bowl and in communication with said concavity, and a smoke conducting stem removably carried by said nipple and having means for detachably projecting into 40 said opening and interlocking with the wall of said bore to prevent removal of said shank from said receptacle and said laterally extending means from said notches.

10. In a pipe, a bowl comprising an expanded part having a tobacco receiving concavity and a reduced part comprising a receptacle in communication with said concavity and including spaced notches; a key having an expanded centrally arranged portion seated on the upper part 50 of said receptacle and including laterally extending means removably received by said notches and including a shank removably projectable into said receptacle and including a substantially rectilinear smoke impinging face spaced from a 55 part of said receptacle and including a bore, said receptacle having an opening, said laterally extending means cooperating with the walls of said notches to locate the wall of said bore in alinement with said opening, a nipple extending laterally of said reduced part of said bowl and in communication with said concavity, and a smoke conducting stem removably carried by said nipple and having means for detachably and frictionally engaging the wall of said bore and the 60 wall of said opening to prevent removal of said shank from said receptacle and said laterally extending means from said notches.
